UNITED STATES PATENT OFFICE.

LOUIS V. BOEHRINGER AND HAROLD THOMASSEN, OF DAYTON, OHIO.

DOOR-LOCK.

1,308,473.

Specification of Letters Patent.

Patented July 1, 1919.

Application filed November 26, 1918. Serial No. 264,200.

To all whom it may concern:

Be it known that we, LOUIS V. BOEHRINGER and HAROLD THOMASSEN, citizens of the United States, residing at Dayton, in 5 the county of Montgomery and State of Ohio, have invented certain new and useful Improvements in Door-Locks, of which the following is a specification.

This invention relates to builders' hardware, and more especially to door securers; and the object of the same is to produce a portable lock by means of which a door can be fastened or secured on the inside so that it will be impossible to open it from 15 the outside.

The object of the invention is to provide a portable device for the use of travelers, whereby doors with imperfect locks or with no locks or keys can be fastened or secured 20 from the inside while the traveler is asleep.

The invention consists specifically in the construction hereinafter more fully described and claimed, and shown in the drawings, wherein

25 Figure 1 is a horizontal section through the free edge of a door and its frame and the keeper therein, and a top plan view of the invention.

Fig. 2 is a section on the line 2—2 of 30 Fig. 1 and

Fig. 3 a section on the line 3—3 of the same view.

The door D closes against a shoulder S in the frame F as usual, and within the 35 frame is the lock keeper K having an opening O for the bolt, which latter is not shown, as it is not necessary to the present invention. In fact, the frame may have the shoulder and keeper and there be no lock 40 at all on the door, or an extremely imperfect one, or the lock may not work or the key may be missing. So long as the frame has the keeper with its opening, our invention is applicable.

45 Coming now to the details of the invention itself, the numeral 1 designates a stout and rather thin strip of metal perhaps six inches in length and an inch in width, having a hook 2 at its front end, a series of 50 teeth 3 along its upper edge, and a transverse pin or stop 4 at its outer end. The strip is quite thin so that it may pass between the free edge of the door D and the frame F, and the hook 2 is of such size that 55 it may pass through the opening O of the

keeper K as illustrated in Figs. 1 and 2. Slidably mounted upon the strip is a plate 5 having preferably near its outer edge a pair of feet 6, and threaded through this plate near its inner edge is a set screw 7. 60 The opening or slot 11 through the plate is so disposed that when the strip is in proper position the feet rest against the frame F and the set screw against the door D. Secured to or formed on the outer face 65 of the plate is a boss 9 having an upright slot 10 whose upper portion is alined with the top of the slot 11, and through these slots the strip passes as seen in Fig. 2. This block is shown as a separate element 70 in the drawings, but it is quite possible to cast integral. The top of the opening in the boss and the opening in the plate are provided with teeth 13 of a size to receive the teeth 3 on the strip. An eccentric 14 75 has its head pivotally mounted at 15 within the slot 10 of the boss and its handle 16 radiating therefrom, the head of the eccentric underlying the lower edge of the strip 1.

In use, the hook 2 is engaged with the opening O in the keeper K, then the door is closed, then the plate 5 and boss 9 are slid up against the door and frame, the set screw striking the door and the feet 6 80 striking the frame as shown in Fig. 1, and the set screw may now be tightened to hold the parts in this position. The handle 16 of the eccentric is then moved downward 85 so that the head 14 raises the strip 1 and moves its teeth 3 into engagement with the teeth 13, and thereafter it is impossible to open the door from the outside or from the inside without first retracting the parts upon the strip so that the set screw no longer 90 strikes the door. Thus is provided a portable door lock which may be used by the traveler in the manner hereinbefore set forth, and by the use of it he is safe from 95 intrusion as suggested.

The foregoing description and the drawings have reference to what may be considered the preferred, or approved form of our invention. It is to be understood that we may make such changes in construction 100 and arrangement and combination of parts, materials, dimensions, et cetera, as may prove expedient and fall within the scope of the appended claim.

Having thus fully described our inven- 110

tion, what we claim as new and desire to secure by Letters Patent is:—

In a door securer, the combination with a strip toothed along its upper edge and hooked at its front end; of a plate having an opening through which said strip passes, a pair of feet projecting forward from the plate at one side of the opening, a set screw through the plate at the other side 10 of its opening; a boss carried by the rear side of said plate and having an upright slot alined with the opening therein, the

top of the slot and opening being toothed, and an eccentric comprising a head pivoted within the slot in the boss and a handle 15 pendant therefrom, for the purpose set forth.

In testimony whereof we affix our signatures in presence of two witnesses.

LOUIS V. BOEHRINGER.
HAROLD THOMASSEN.
